UNITED STATES PATENT OFFICE

ARTHUR E. REUSS, OF CINCINNATI, OHIO, ASSIGNOR TO THE GENERAL IRON WORKS COMPANY, OF CINCINNATI, OHIO, A CORPORATION OF OHIO

HEATING DEVICE

Application filed April 20, 1928. Serial No. 271,636.

My invention is an improvement upon the heating device shown, described and claimed in my copending application for patent on heaters, Serial No. 223,666, filed October 3, 8 1927.

It is the object of my invention to provide a new and improved heater in which the fluid being heated is forced to move in a general path reverse to its natural direction of movement, and to provide a novel arrangement of deflectors whereby cross fluid currents are shunted from a column of the fluid and again reunited as a column after having heat imparted thereto; and, further, to provide a 10 novel arrangement of passages for the fluid being heated comprising main passages which are substantially upright and cross-passages which are arranged one above the other and are separated in layers which are 15 substantially horizontal by passages for the heating medium arranged one above the other between the cross-passages for the fluid being heated.

It is the object of my invention further to 20 provide deflectors forming openings of varying sizes for controlling the flow of the fluid being heated between substantially upright passages for the fluid; and, further, to provide a descending column of fluid to be heated arranged to be directed into cross-passages separated in up and down relation by crossing passages of heating medium and again united in a descending column; further, to cause said descending column to pass about a 25 fire-box; and, further, to provide descending columns of fluid being heated connected by cross-passages which are separated by cross-passages for the heating medium, the said cross-passages located one above the other.

The invention will be further readily understood from the following description and claims, and from the drawings, in which latter:

Fig. 1 is a perspective view of my improved device, partly broken away.

Fig. 2 is a vertical cross-section of a portion of my improved device, taken on the line 2-2 of Fig. 1.

Fig. 3 is a vertical longitudinal section of 50 my improved device, taken in the plane of

the line 3-3 of Fig. 4, and partly broken away.

Fig. 4 is a vertical cross-section of my improved device, taken in the plane of the line 4-4 of Fig. 3, and partly broken away. 55

Fig. 5 is a horizontal section of my improved device, taken in the plane of the irregular line 5-5 of Fig. 4.

The fuel for heating my improved heater is exemplified as gas, although other fuel, either solid, liquid or gaseous, may be employed. A fire-box 11 has the fuel element 60 therein, represented as a gas-burner 12. The body of the fire-box is shown of rectangular form. 65

Passages 15 for the fluid being heated are shown rectangular in cross-section provided with upper walls 16; lower walls 17 and side walls 18, 19. These passages are open-ended as shown at 20, 21. The walls form flat 70 rectangular tubes made out of metal sheeting connected at their edges for making tight joints. The lower one of these passages, has side walls 22, 23, which project downwardly 75 and connect with the fire-box with a sealed joint.

These passages are arranged one above the other in the heater, and are spaced apart by spaces 25, which form passages crossingly arranged with relation to the passages 15, and 80 are also preferably rectangular in cross-section.

The respective ends of the upper wall and the lower wall of the respective passages 15 are bent away from said passages to form side walls 26, 27, for the respective passages 25 and have sealed joints for forming said cross-passages 25. The passages 25 are open-ended as shown at 28, 29. 85

Deflectors 31, 32, 33, 34, 35, project from one of the ends of the respective cross-passages 15 into a main supply passage 36 formed by the side walls at one of the sides of the passages 25, a wall 37 parallel with said sides 90 and merging with the deflector 35, which deflector forms the bottom of said main supply passage, the ends of the supply passage being formed by end walls 38, 39. The ends 95 of the deflectors are connected with said end 100

walls. The passage 36 forms the supply passage for the fluid being heated.

These deflectors are shown as successively extending increasing distances into the supply passage for respectively shunting portions of the current in the supply passage into the various cross-passages 15.

A second main passage 41 is at the other end of said cross-passages 15, and is formed for instance by the other side walls 26 of said cross-passages 25, a wall 42 parallel therewith and end walls 43, 44. The passage 41 is the discharge passage for the cross-passages 15.

Deflectors 45, 46, 47, 48 and 49 extend into said second discharge passage preferably from the upper walls of said cross-passages 15, except from the lowest one of said cross-passages. These deflectors preferably also extend into said discharge passage to various extents, the upper one 45 of the deflectors forming the upper wall of said discharge passage. The supply passage 36 and the discharge passage 41, are preferably of rectangular form in cross-section, extending cross-wise of the cross-passages 15 throughout the lengths of the cross-passages 25.

The supply passage and the discharge passage preferably extend up and down and have the fluid to be heated, instanced as air, preferably forced downwardly therein, the currents of air being divided between said supply passage and said discharge passage into a multiple of cross-passages for dividing the incoming air into a number of cross-currents which are heated to different extents according to their distance from the fire-box, these cross-currents being again united into a descending current having equalized temperature, this descending current being preferably passed around the fire-box for receiving additional heat.

The lower end 50 of the wall 42 of the second main passage is bent to form a deflector for directing the combined currents into the lowermost one of the cross-passage 15, the lower part of said lowermost cross-passage 15 being formed by the upper wall of the fire-box. The direction of travel of the fluid being heated in the lowermost cross-passage 15 is reverse to the direction of travel of said fluid through the cross-passages 15 thereabove.

A deflector 55 at the end of the lowest cross-passage 15 directs the current of heated fluid into a passage 56 which is shown as a passage extending about the fire-box. The inner side wall of said extension is formed by the fire-box, the outer side wall being formed by a wall 57, and said passage 56 being provided with suitable end walls 58, 59, at the respective ends of the fire-box for forming said passage with sealed joints. A passage extension 60 connects with the upwardly extending leg of the passage 56 and is connected with said extension 56 with the sealed

joint. The passage 60 has an inner wall 61, an outer wall 62, and end walls formed by extensions of the end walls 43, 44, all suitably connected with suitable sealed joints.

The cross-passages 15 extend throughout the major portion of the width of the furnace. The direction of movement of the fluid being heated in said passages and in the main passages and extension passages is indicated by the arrows *a*. The air is received through an inlet port 65, and is exemplified as having a generally downward course and a course which is crosswise to the passages 25 and is around the bottom of the fire-box and then ascends in the ascending stretch of the passage and is received through a discharge port 66 in said passage.

The fluid being heated is preferably forced in a downward direction reverse to the direction of natural flow of heated fluid, which would be upward. The fluid, namely the air to be heated, is forced downward, as by means of a blower 71, which comprises an electric motor 72 and a fan 73 in an intake chamber 74, to which a pipe 75 may lead from a suitable source, as from the outside air or the air may be received through said pipe from the house or rooms or space to be heated. A hood 76 is located between the blower and the inlet port 65 and directs the air into the main air supply passage of the heater.

The heated air is discharged through the outlet port 66. It may, if desired, enter a hood 79, which directs the heated air into a drum 80, from which suitable heating pipes, shown at 81, and provided with the usual dampers 82, direct the heated air to the desired point of use, as to the various rooms in the dwelling or to other spaces to be heated, or said heated air may assume any other course.

The products of combustion are received through an opening 85 in the rear wall of the fire-box. The respective upper walls and lower walls of the passages 15 spaced above the fire-box form respectively the lower wall and the upper wall of the passages 25, crossingly arranged with relation to the first-named passages, the side walls of said last-named passages being formed by the bent ends of the upper and lower walls of the first-named passages 15 spaced above the fire-box, as hereinbefore explained.

The ends of neighboring passages 25 above one another are connected at the respective ends of said passages by means of deflectors 86, 87, which are formed in deflector sheets 88, 89, at the respective ends of the passages 25, and are suitably connected with the respective sides of alternating passages 15, and with the fire-box, by means of sealed joints for forming connecting passages 90, 91, at the respective ends of the passages 25, and a connecting passage 92 between the opening 85.

and the lowermost cross-passage 25. The inner wall of said last-named connecting passage is formed by the side wall of the lowest fluid passage 15. The upper cross-passage 25 is provided with an outlet port 95. The cross-passages 25, the connecting passages 90, 91, 92, and the outlet port 95, extend preferably throughout the lengths of the fluid passages 15.

A serpentine passage extending back and forth and in general upward direction is thus provided for the products of combustion, the course of the products of combustion being indicated by the arrows *b*. The products of combustion have a serpentine course back and forth between the cross-passages 15, through which the fluid being heated moves from the supply passage 36 to the discharge passage 41. The products of combustion are separated from the fluid being heated by the single thickness of sheet metal which forms the dividing wall between the cross-passages through which the products of combustion and the fluid respectively pass, providing for extreme transference of heat to said fluid. An outer casing 96 is provided for the heater which may be provided with a lining of insulation 97.

The passages 15 and 25 extend substantially throughout the horizontal cross-sectional area of the heater.

In my improved device the incoming column of air is divided for being apportioned among the respective cross-passages 15, and the successive deflectors extend into the supply passage in increasing ratio. Thus assuming that 700 cubic feet of air per minute are being delivered to the intake opening and there are five cross-passages to be fed by said supply passage, the deflector 31 extends into the supply passage to divert one-fifth of the incoming air or other fluid into the upper cross-passage 15. The next deflector 32 extends into the supply passage for about one-fourth the area of the supply passage for diverting or shunting one-fourth of the balance of the supply current into the second cross-passage 15. The third deflector 33 extends into the supply passage for about one-third the area of the supply passage for deflecting one-third of the balance of the supply current into the cross-passage 15. The fourth deflector 34 extends into the supply passage for about one-half the cross-sectional area of the supply passage, for deflecting about one-half of the balance of said main current into the fourth cross-passage 15, the balance of the main current being deflected into the bottom cross-passage 15 spaced from the fire-box opening at that side of the heater. This arrangement results in supplying a substantially equal amount of fluid being heated to each of the cross-passages, namely, one hundred and forty cubic feet of air in the example stated.

I have shown a reverse arrangement of deflectors at the other of the ends of the cross-passages 15. The upper deflector 45 extends across the entire cross-sectional area of the main outlet or discharge passage 41; the second deflector 46 extends into the discharge passage for about one-half the cross-sectional area of said discharge passage; the third deflector 47 extends into the cross-sectional area of the discharge passage to cover one-third its area; the fourth deflector 48 extends into said discharge passage for one-fourth its area, and the lower deflector 49 extends into said discharge passage for one-fifth its area, for receiving proportional discharges from the respective cross-passages 15 spaced from the fire-box and combining the discharges from said cross-passages and causing the same to be mingled and moved into the lowermost passage 15, where-in it moves in opposite direction. The cross currents of fluid are thereby heated in separate layers for transferring heat from the products of combustion quickly to the divided cross-currents of fluid being heated, and permitting quick and effectual heating of said cross-currents, and producing a combined heated column of heated fluid, which in the present instance is a descending column, which is caused to flow about the fire-box, and then ascends to the point or points of delivery of the heated fluid.

In my improved device the incoming air is under pressure of the blower and is forced through the main intake passage, the pressure being reduced successively as the successive portions of incoming air are shunted into the cross-passages, the pressure being again built up as the cross-currents of air are discharged from the cross-passages into the discharge column of air.

It is obvious that changes may be made in the preferred embodiment and example of my invention herein shown and described without departing from the spirit of my invention disclosed in the accompanying claims.

I do not herein claim the construction, form or arrangement of passages for the fluid being heated or for the products of combustion, nor their relative arrangement, nor their arrangement with relation to the fire-pot, nor the means for connecting the same respectively, nor the means for creating, forming or controlling the directions of movement of the currents respectively of fluid being heated or the products of combustion, nor the means for forming the passages, nor the structure or arrangement of the furnace, nor the structure and arrangement of means for causing reverse travel of the fuel being heated and the products of combustion, herein shown and described, having shown, described and claimed the

same in my aforesaid copending application Serial No. 223,666.

Having thus fully described my invention, what I claim as new, and desire to secure by Letters Patent, is:

- 5 1. A heater of the character described comprising a series of cross-passages for the fluid being heated, passages for the products of combustion which separate said cross-passages, said passages arranged one above the other, a continuous upright inflow passage common to all said cross-passages at one of the ends of said cross-passages, a continuous 10 upright outflow passage common to all said cross-passages at the other of the ends of said cross-passages, means for forcing the fluid being heated through said inflow passage, said cross-passages and said outflow passage in a general direction reverse to the 15 direction of natural flow of said fluid being heated and forcing said fluid being heated in a common direction through said cross-passages from said inflow passage into said outflow passage, an additional cross-passage 20 below said first-named cross-passages, said additional cross-passage connecting with the lower end of said outflow passage and directing the flow of said fluid therethrough in a direction opposite to said common direction, and a continuation passage connecting with said additional cross-passage and extending 25 downwardly, then crosswise in said common direction and then upwardly continuously alongside said continuous upright outflow passage. 30 2. A heater of the character described comprising a series of cross-passages for the fluid being heated, passages for the products of combustion which separate said cross-passages, said passages arranged one above the other, a continuous upright inflow passage common to all said cross-passages at one of the ends of said cross-passages, deflectors for the respective cross-passages of said series of cross-passages, said deflectors extending into 35 said continuous upright inflow passage to different extents increasingly downward for dividing the current of fluid being heated in said inflow passage substantially equally among said cross-passages, a continuous upright outflow passage common to all said cross-passages at the other of the ends of said cross-passages, and means for forcing the fluid being heated through said inflow passage, said cross-passages and said outflow passage, said 40 sage in a general direction reverse to the direction of natural flow of said fluid being heated and forcing said fluid being heated in a common direction through said cross-passages from said inflow passage into said outflow passage. 45 3. A heater of the character described comprising a series of cross-passages for the fluid being heated, passages for the products of combustion which separate said cross-passages, said passages arranged one above the 50 other, a continuous upright inflow passage common to all said cross-passages at one of the ends of said cross-passages, deflectors for the respective cross-passages of said series of cross-passages, said deflectors extending into said continuous upright inflow passage to different extents 55 increasingly downward and said deflectors at the other of the ends of said cross-passages extending into said continuous upright outflow passage to less extents downwardly, means for forcing the fluid being heated through said inflow passage, said cross-passages and said outflow passage in a general direction reverse to the direction of natural flow of said fluid being heated and forcing said fluid being heated in a common direction through said cross-passages from said inflow passage into said outflow passage, an additional cross-passage below said first-named cross-passages, said additional cross-passage connecting with the lower end of said outflow passage and directing the flow of said fluid therethrough in a direction opposite to said common direction, and a continuation passage 60

connecting with said additional cross-passage and extending downwardly, then cross-wise in said common direction and then upwardly continuously alongside said continuous upright outflow passage.

5 In testimony whereof, I have hereunto signed my name.

ARTHUR E. REUSS.
